UNITED STATES PATENT OFFICE.

MARTIN BRANDON, OF TOLEDO, OHIO.

CONTAINER AND METHOD OF MANUFACTURING SAME.

Application filed November 22, 1926. Serial No. 149,836.

This invention relates to containers and to the manufacture thereof, and particularly to hat boxes, packing cases and the like.

The object of the invention is the provision of a fibre board container of this character which is simple, strong and durable in its construction, easy and inexpensive to manufacture, and has a reinforced edge which forms an internal shoulder against which the end closure member of the container, whether it be the bottom or the top, is adapted to seat.

The invention is fully described in the following specification, and two embodiments thereof illustrated in the accompanying drawings, in which,—

Figure 1 is a side elevation of a container of the hat box type embodying the invention. Fig. 2 is a different elevation thereof with a part in section on the line 2—2 in Fig. 1. Fig. 3 is a fragmentary sectional enlargement of a corner portion of the section in Fig. 2. Fig. 4 is a view similar to Fig. 2 of a slightly different form of the invention. Fig. 5 is a section on the line 5—5 in Fig. 4, and Fig. 6 is a fragmentary sectional enlargement of a corner portion of the section in Fig. 4.

Referring to the drawings, 1 designates the body portion of the container and 2 the top thereof, which, in the present instance, is adapted to have a telescoping fit down over an edge portion of the body. The body 1 has a main sidewall 3, shaped to suit the desired form of the container, and which, in the case of a hat box, is of circular form, except for a flattened portion at one side thereof. The wall 3 is preferably formed by rolling a thin strip of fibre board on a mandrel so that the body is built up of several ply or thicknesses of the material glued one to another and is of endless form circumferentially thereof, thereby providing a body of strong and durable construction which is devoid of seams or lapped joints, as is the case where a strip of material is bent into the desired form with its meeting ends joined together in lapping or end abutting relation.

50 A bead member 5 of reed, wire or other suitable material is positioned within the outer marginal end portion of the wall 3 and extends entirely therearound. This member is intended to form a shoulder within the wall 3 against which the edge

of a bottom member 6 may seat, and may be retained to the wall by extending the outer facing material 7 of the wall around the outer end edge of the wall and the member 5, and is secured at its free edge against the inner side of the wall 3, as shown in Figs. 4 and 6. Another simple method of retaining the member 5 to the wall consists in securing a separate fabric strip 8 to the outer side of the wall by sewing 9, or in any other suitable manner, and then doubling it over upon itself so as to cover the stitching and to enable it to be wrapped around the end edge of the wall and the member 5, the same as in the case of the facing strip 7, as shown in Figs. 2 and 3. In this case, the facing strip 7 if used is preferably terminated at the outer end edge of the wall. The facing material 7 and/or the end edge wrapping material 8 may be of leather, fabric or other material suitable for the purpose. It is apparent that this not only provides an efficient seat for the bottom within the outer end edge portion of the wall, but also provides a broadened end edge for the wall and materially strengthens the same.

In the case of the body 1, where it is desired to telescope the cover 2 therewith, a lining 10, preferably of the same nature and form as the body wall 3, is fitted in said wall and bears at its inner end edge against the marginal edge portion of the bottom 6 to retain it to its seat on the shoulder formed by the member 5. The lining 10 is of sufficient depth to project a short distance above the wall 3 to provide an extension over which the edge of the cover member 2 may telescope. The lining 10 is preferably faced with a suitable material 11 of fabric, paper or the like, and the lower inner end edge of this material is extended out over the adjacent edge portion of the bottom 6 and glued or otherwise suitably secured thereto, as indicated at 12.

It is apparent that in the drawing the thickness of the facing materials is exaggerated and that in reality they are so thin that instead of the wall 3 and lining 10 being held spaced apart thereby, as shown, they will substantially bear against each other.

105 The cover 2 is constructed in the same manner as the body 1, except that the lining member 10 is omitted. In the drawings the outer facing material for the body wall portion of the cover is extended around the 110

inner edge thereof and thence inwardly to the edge of the top member 13 over which it laps.

It is apparent that I have provided a container suitable for use as a hat box, or a packing case, and which is strong and durable in its construction and easy and inexpensive to manufacture.

I wish it understood that my invention is not limited to any specific construction, arrangement, or form of the parts, as it is capable of numerous changes and modifications without departing from the spirit of the claims.

Having thus described my invention, what I claim as new and desire to secure by Letters Patent is:

1. In a container, an outer wall, a bead member disposed within said wall adjacent its lower edge, a binding strip secured to the outer wall and extending downwardly and inwardly beneath the wall and bead member and having its free end extending upwardly over the bead member and engaging the inner side of said wall to form a substantially right angular integral shoulder, a bottom wall seating at its lower face and at its peripheral edge on said shoulder, and an inner wall seating at its lower edge on the bottom wall and having its outer face engaging the free end of the binding strip.

2. In a container, an outer wall, a bead member disposed within said wall adjacent its lower edge, a binding strip secured to the outer wall and extending downwardly and inwardly beneath the wall and bead member and having its free end extending upwardly over the bead member and engaging the inner side of said wall to form a substantially right angular integral shoulder, a bottom wall seating at its lower face and at its peripheral edge on said shoulder, and means disposed within said outer wall and

seating at its lower edge on the lower wall and having its outer face engaging in the free end of the binding strip.

3. A container having an outer wall of fibrous material and of endless form circumferentially of the container, a bead member seated within the outer margin and edge of said wall, a pliant material secured to the outer side of the wall and extending around its outer end edge and said bead member and secured to the inner side of the wall, thereby cooperating with the bead member to form an integral shoulder and serving to retain the bead member to the wall, an end closure member for the wall disposed therein and having one of its faces seating outwardly against the shoulder formed by the bead member, said closure having its peripheral edge contacting with one end of the pliant material to retain the same, and a lining member fitted into said outer wall and having an inwardly extending flange adapted to engage said end closure member to retain the latter to its seat, said lining having its outer face engaging the inner end of the pliant material.

4. A container, including a body having inner, outer and intermediate walls, a bead member disposed within said intermediate wall adjacent its lower edge, said outer wall having its lower portion extending inwardly and upwardly over the bead member and terminating between the inner and intermediate walls, and an end closure for the container seated upon said bead member and having a portion disposed beneath the inner wall and having its peripheral edge engaged with the upwardly extending portion of the outer wall to retain the same.

In testimony whereof I have hereunto signed my name to this specification.

MARTIN BRANDON.
